UNITED STATES PATENT OFFICE

171,209

ROCKING CHAIR

James E. Jones, Toledo, Ohio, assignor to The Hettrick Manufacturing Company, Toledo, Ohio, a corporation of Ohio

Application May 5, 1953, Serial No. 24,860

Term of patent 14 years

(Cl. D15—6)

To all whom it may concern:

Be it known that I, James E. Jones, a citizen of the United States and a resident of Toledo, Lucas County, Ohio, have invented a new, original, and ornamental Design for a Rocking Chair, of which the following is a specification, reference being had to the accompanying drawing, forming a part thereof.

In the drawing:

Figure 1 is a front perspective view of a rocking chair, showing my new design;

Figure 2 is a rear end elevation of the rocking chair; and

Figure 3 is a side elevation of the rocking chair.
I claim:
The ornamental design for a rocking chair, as shown.

JAMES E. JONES.
